RETRACTABLE CONTAINER SPOUT

Roy Corella, Los Angeles, Calif.

Application December 27, 1955, Serial No. 555,363

7 Claims. (Cl. 222—517)

This invention relates to a retractable spout for containers.

It is an object of my invention to provide a spout which is adapted to be used with substantially any type of container, whether the same be formed of metal, glass, plastic, or other material.

It is a further object of my invention to provide such a spout which is automatic in operation in the sense that it is adapted to fit and be held within the neck of the container directly beneath the cap when the cap is on the container. When the cap is removed, the spout automatically moves out of the neck of the container and assumes a pouring position adjacent the lip of the neck. When the cap is replaced on the container, the top of the spout is caught in the cap and carried back into the neck of the container with the same movement which replaces the cap.

It is particularly an object of my invention to provide such a spout which is adapted to be installed in or removed from the neck of the container after the container has been filled.

While my spout is particularly adapted and designed for containers having screw threaded necks with removable caps, it is also capable of use with or without modification on other types of containers as well.

It is another object of my invention to provide a spout of the class described which is simple and economical to manufacture, so that it is capable of widespread sale and use.

The advantages of a spout of the type described are believed to be substantially obvious. It provides the convenience of a pouring spout at all times, without requiring the attachment and removal of the spout for each pouring operation. The fact that my spout is attachable and removable after the container has been filled is believed to be of particular importance, since the spout does not interfere with the filling of the container and since the spout can be removed when the container is empty and used a considerable number of times.

My invention also comprises such other objects, advantages and capabilities as will later more fully appear and which are inherently possessed by my invention.

While I have shown in the accompanying drawings a preferred embodiment of my invention, it should be understood that the same is susceptible of modification and change without departing from the spirit of my invention.

Referring to the drawings, Fig. 1 is a top plan view of a container and with the cap removed and my spout in pouring position;

Fig. 2 is a side view of the same with the cap shown in full lines and the movement of the spout indicated by dotted lines and arrows;

Fig. 3 is a sectional view taken on line 3—3 of Fig. 1;

Fig. 4 is a perspective view of the preferred embodiment of my spout;

Fig. 5 is a top plan view of another embodiment of my spout in pouring position on a container;

2

Fig. 6 is a perspective view of the spout shown in Fig. 5;

Fig. 7 is a sectional view similar to Fig. 3, but showing the spout in retracted position within the neck and upper part of the container.

Fig. 8 is a perspective view of a more simplified embodiment of my invention.

My spout is adapted to be used with a container 10, having a top 11 with an upstanding open circular neck 12, through which the contents are inserted into and removed from the container 10. The outside of the neck 12 is provided with screwthreading 13. A circular cap 14 is provided with internal screwthreading 15 which is complementary to the screwthreading 13 on neck 12.

15 The top of the neck 12 is provided with an integral downwardly directed lip 16 which extends around its entire circumference.

A preferred embodiment of my spout which has been selected to illustrate my invention comprises a funnel portion 17 which is preferably formed of metal, although any suitable material may be used. The funnel portion 17 includes a bottom pouring channel 18 and a pair of integral upwardly directed side walls 19 and 20. The funnel portion 17 is tapered in the conventional manner, 20 with the side walls 19 and 20 converging toward the end of pouring channel 18.

Integral with the funnel portion 17 is a downwardly extending rear wall 21, which extends at a right angle from the back of pouring channel 18. The rear wall 21 is curved in an arc corresponding to the curve of the neck 12 with which my spout is used.

The bottom of the rear wall 21 is provided with a forwardly direct rightangular integral catch portion 22, extends substantially parallel to the pouring channel 18.

35 The distance between catch portion 22 and channel 18 is greater than the distance from the top of the neck 12 to the bottom of its downwardly directed lip 16.

Attached to funnel portion 17 adjacent the center of rear wall 21 is a spring receiving member 23. The spring 40 receiving member 23 extends outwardly from rear wall 21 and then downwardly at a right angle to provide a hook which is open at the bottom to receive a portion of the end of a spring 24. The spring 24 is elongated, with one end 25 being formed into a substantially complete circle having a diameter slightly greater than the diameter of neck 12. The spring continues with an integral straight portion 26 which extends diametrically across the circle and which simultaneously extends upwardly. The opposite end of the spring 24 is formed 50 into a triangular portion 27, the base of which is disposed within the spring receiving member 23.

My spout thus comprises a funnel portion 17 and an attached spring 24. The circular portion of the spring 24 is adapted to fit within the neck 12 of a container 55 10, lying within the concave portions formed by the screwthreading 13. The circular portion of ring 24 is contracted to permit its insertion into the neck 12 and then expands to bear against the inside of the neck 12 to maintain a fixed position therein.

60 When my spout is in retracted position, it is held within the neck 12 and the upper portion of the container 10, with the funnel portion 17 extending substantially vertically, its tip bearing against the inside of the cap 14. When the cap 14 is removed from the container, 65 the straight portion 26 of spring 24 moves the funnel portion 17 upwardly. The funnel portion 17 is urged in a vertical direction until its catch portion 22 engages the downwardly directed lip 16 of neck 12 to prevent further vertical movement of the funnel portion 17. The 70 spring 24 continues to exert upwardly directed pressure against the spring receiving member 23, causing the funnel portion 17 to pivot on lip 16 and move into horizontal

pouring position. During this movement, the lip 16 fits within the area between the pouring channel 18 and catch portion 22.

When the cap 14 is replaced, the user catches the tip of funnel portion 17 within the cap and carries it into the neck 12 and container 10 with substantially the same motion which replaces cap 14 on neck 12. This requires that the end of the funnel portion 17 be raised slightly and then moved vertically downwardly as indicated in Fig. 2 of the drawings.

Another embodiment of my invention is shown in Figs. 5 and 6 of the drawings. It comprises a funnel portion 17a having portions 18a-22a, which are identical with portions 18-22 of funnel portion 17. Extending across the inner surface of the rear wall 21a is a spring receiving member 30, the ends of which are attached to the rear wall 21a and the central portion of which is bent outwardly therefrom to receive the end of a leaf spring 31. The opposite end of the leaf spring 31 is attached to the center of a semi-circular ring 32.

The semi-circular ring 32 comprises somewhat more than half a circle and is slightly larger in diameter than the neck of the container. It fits within the neck 12a of the container. The leaf spring 31 acts in the same manner as the previously described straight portion 26 of spring 24, acting to urge the funnel portion 17a upwardly into pouring position.

Another and more simplified embodiment of my invention, which is shown in Fig. 8 of the drawings, comprises a funnel structure similar to that previously described and which operates in the same manner. The spring structure, however, has been reduced to the simple form of a single elongated flat spring 40, which is attached at one end to the funnel and the other end of which is free and is provided with a small hook portion 41.

In use, the hook portion 41 engages one of the concave portions of the screwthreading 13 directly beneath the lip 16. The spring 40 extends diametrically across the top of the container 10. The spring 40 is provided with a slight downward bow when the funnel is in pouring position and a much greater bow when the funnel is in retracted position. This embodiment of my invention has the advantage of being extremely simple and economical to construct and simple to install and remove.

I claim:

1. A retractable container spout for use in combination with a container having a screwthreaded circular neck, a screwthreaded cap removably mounted thereon and a downwardly directed lip extending around the top of the neck, said spout comprising a funnel portion having a bottom pouring channel and a pair of upwardly directed side walls formed integrally therewith, a rear wall extending downwardly at substantially a right angle along the entire rear edge of said funnel portion, said rear wall having a catch portion extending forwardly therefrom at substantially a right angle, said rear wall and catch portion being curved in an arc corresponding to the neck of said container, the inner surface of said rear wall having a spring receiving portion, a spring formed from a single piece of wire, said spring having a circular portion at one end thereof, said circular portion being greater in diameter than the diameter of the neck of said container, said spring having a straight portion extending diametrically across said circular portion and upwardly directed therefrom, the other end of said spring engaging the spring receiving portion of said rear wall, said spout adapted to be removably mounted within the neck and upper portion of said container with the circular portion of said spring fitting within the screwthreaded portion of the neck, said funnel portion being movable between a pouring position in which it extends horizontally outwardly from the edge of the neck and a retracted position in which it extends substantially vertically within

the neck and upper portion of the container, the catch portion of said funnel portion being disposed beneath and adapted to pivotally engage the lip of the neck to permit said funnel portion to be pivoted between vertical and horizontal positions, the circular portion of said spring holding said spout within said container, the straight portion of said spring resiliently urging said funnel portion upwardly and pivotally to pouring position when the cap is removed from the container, the end of said funnel portion being adapted to fit within the cap for movement of said funnel portion from said pouring position to retracted position.

2. A retractable container spout for use in combination with a container having a screwthreaded circular neck, a screwthreaded cap removably mounted thereon and a downwardly directed lip extending around the top of the neck, said spout comprising a funnel portion having a bottom pouring channel and a pair of upwardly directed side walls, a rear wall extending downwardly along the rear edge of said funnel portion, said rear wall having a catch portion extending forwardly therefrom, said rear wall and catch portion being curved in an arc corresponding to the neck of said container, the inner surface of said rear wall having a spring receiving portion, a spring having a circular portion, said circular portion being greater in diameter than the neck of said container, said spring having a straight portion extending diametrically across said circular portion and upwardly directed therefrom, one end of said straight portion engaging the spring receiving portion of said rear wall, said spout adapted to be removably mounted within the neck and upper portion of said container with the circular portion of said spring fitting within the screwthreaded portion of the neck, said funnel portion being movable between a pouring position in which it extends horizontally outwardly from the edge of the neck and a retracted position in which it extends substantially vertically within the neck and upper portion of the container, the catch portion of said funnel portion being disposed beneath and adapted to pivotally engage the lip of the neck to permit said funnel portion to be pivoted between vertical and horizontal positions, the circular portion of said spring holding said spout within said container, the straight portion of said spring resiliently urging said funnel portion upwardly and pivotally to pouring position when the cap is removed from the container, the end of said funnel portion being adapted to fit within the cap for movement of said funnel portion from said pouring position to retracted position.

3. A retractable container spout for use in combination with a container having a screwthreaded circular neck, a screwthreaded cap removably mounted thereon and a downwardly directed lip extending around the top of the neck, said spout comprising a funnel portion having a bottom pouring channel and a pair of upwardly directed side walls, a rear wall extending downwardly along the rear edge of said funnel portion, said rear wall having a catch portion extending forwardly therefrom, said rear wall and catch portion being curved in an arc corresponding to the neck of said container, the inner surface of said rear wall having a spring receiving portion, a rounded spring greater in diameter than the neck of said container, a straight spring extending diametrically across said rounded spring and upwardly directed therefrom, one end of said straight spring being attached to said rounded spring, the other end of said straight spring engaging the spring receiving portion of said rear wall, said spout adapted to be removably mounted within the neck and upper portion of said container with said rounded spring fitting within the screwthreaded portion of the neck, said funnel portion being movable between a pouring position in which it extends horizontally outwardly from the edge of the neck and a retracted position in which it extends substantially vertically within the neck and upper portion of the container, the catch portion of said funnel portion

being disposed beneath and adapted to pivotally engage the lip of the neck to permit said funnel portion to be pivoted between vertical and horizontal positions, said rounded spring holding said spout within said container, said straight spring resiliently urging said funnel portion upwardly and pivotally to pouring position when the cap is removed from the container, the end of said funnel portion being adapted to fit within the cap for movement of said funnel portion from said pouring position to retracted position.

4. A retractable container spout for use in combination with a container having a circular neck, a cap removably mounted thereon and a downwardly directed lip extending around the top of the neck, said spout comprising a funnel portion, said funnel portion having a pouring surface and a catch portion disposed therebeneath, the distance between said pouring surface and catch portion being greater than the downward thickness of the lip of said container, a rounded spring greater in diameter than the neck of said container, a straight spring extending diametrically with respect to said rounded spring and upwardly directed therefrom, one end of said straight spring being attached to said rounded spring and the other end being attached to said funnel portion, said rounded spring being adapted to fit within said neck, said funnel portion being movable between a pouring position in which it extends horizontally outwardly from the edge of the neck and a retracted position in which it extends substantially vertically within the neck and upper portion of the container, said catch portion being disposed beneath and adapted to pivotally engage the lip of the neck to permit said funnel portion to be pivoted between vertical and horizontal positions, said rounded spring holding said spout within said container, said straight spring resiliently urging said funnel portion upwardly and pivotally to pouring position when the cap is removed from the container, the end of said funnel portion being adapted to fit within the cap for movement of said funnel portion from pouring position to retracted position.

5. A retractable container spout for use in combination with a container having a circular neck, a cap removably mounted thereon and a downwardly directed lip extending around the top of the neck, said spout comprising a funnel portion, said funnel portion having a pouring surface and a catch portion disposed therebeneath, the distance between said pouring surface and catch portion being greater than the downward thickness of the lip of said container, first spring means greater in diameter than the neck of said container, second spring means extending diametrically with respect to said first spring means and upwardly directed therefrom, said first spring means being adapted to fit within said neck, said funnel portion being movable between a pouring position in which it extends horizontally outwardly from the edge of the neck and a retracted position in which it extends substantially vertically within the neck and upper portion of the container, said catch portion being disposed beneath and adapted to pivotally engage

the lip of the neck to permit said funnel portion to be pivoted between vertical and horizontal positions, said first spring means holding said spout within said container, said second spring means resiliently urging said funnel portion upwardly and pivotally to pouring position when the cap is removed from the container, the end of said funnel portion being adapted to fit within the cap for movement of said funnel portion from pouring position to retracted position.

10 6. A retractable container spout for use in combination with a container having a neck, a cap removably mounted thereon and a downwardly directed lip disposed adjacent the top of the neck, said spout comprising a funnel portion, said funnel portion having a pouring surface and a catch portion disposed therebeneath, the distance between said pouring surface and catch portion being greater than the downward thickness of the lip of said container, said funnel portion being movable between a pouring position in which it extends horizontally outwardly from the edge of the neck and a retracted position in which it extends substantially vertically within the neck and upper portion of the container, said catch portion being disposed beneath and adapted to pivotally engage the lip of the neck to permit said funnel portion to be pivoted between vertical and horizontal positions, spring means removably holding said spout within said neck and the upper part of said container, and spring means resiliently urging said funnel portion upwardly and pivotally to pouring position when the cap is removed from the container, the end of said funnel portion being adapted to fit within the cap for movement of said funnel portion from pouring position to retracted position.

7. A retractable container spout for use in combination with a container having a neck, a cap removably mounted thereon and a downwardly directed lip disposed adjacent the top of the neck, said spout comprising a funnel portion, said funnel portion having a pouring surface and a catch portion disposed therebeneath, the distance between said pouring surface and catch portion being greater than the downward thickness of the lip of said container, said funnel portion being movable between a pouring position in which it extends horizontally outwardly from the edge of the neck and a retracted position in which it extends substantially vertically within the neck and upper portion of the container, said catch portion being disposed beneath and adapted to pivotally engage the lip of the neck to permit said funnel portion to be pivoted between vertical and horizontal positions, 40 means holding said spout within said container, and means resiliently urging said funnel portion upwardly and pivotally to pouring position when the cap is removed from the container, the end of said funnel portion being adapted to fit within the cap for movement of said funnel portion from pouring position to retracted position.
